UNITED STATES PATENT OFFICE.

CHARLES F. HALDEMAN, OF SALEM, OHIO, ASSIGNOR TO THE SILVER MANUFACTURING COMPANY, OF SALEM, OHIO, A CORPORATION OF OHIO.

GEARING.

1,121,921.

Specification of Letters Patent.

Patented Dec. 22, 1914.

Application filed May 31, 1912. Serial No. 700,563.

To all whom it may concern:

Be it known that I, CHARLES F. HALDEMAN, a citizen of the United States, residing at Salem, in the county of Columbiana and 5 State of Ohio, have invented a new and useful Improvement in Gearing, of which the following is a specification.

My invention relates to improvements in gearing construction, the objects being, first, 10 to provide mechanism for actuating the feed, the endless feed belts and the various rollers in connection therewith, and second, to provide means for reversing the rotation of the lower endless conveyer belt. These objects 15 together with other objects readily apparent to those skilled in the art I attain by the mechanism illustrated in the accompanying drawings, in which—

Figure 1 is a longitudinal vertical section. 20 Fig. 2 is a side elevation. Fig. 3 is a top view showing the upper endless compressor belt removed. Fig. 4 is a sectional view on an enlarged scale of the clutch members and the different parts belonging to and pertaining 25 to the clutches and their respective gears. Fig. 5 is a detached perspective view of the inner clutch wheel. Fig. 6 is a detached perspective view of the outer clutch wheel. Fig. 7 is a detached perspective view of the 30 reverse lever. Fig. 8 is a detached perspective view of the clutch member fixed to and rotatable with the lower endless conveyer propelling shaft. Fig. 9 is a detached perspective view of the gear driving wheel, its 35 pinion and clutch.

Similar numerals of reference indicate corresponding parts in all the figures of the drawings.

In the accompanying drawing, 1 represents in a conventional way, a feed cutter 40 frame which is constructed in the usual manner, reference being had to the proper assembling and arrangement of the various movable and rotatable parts designed and calculated to be carried by said frame. The cutter head shaft 2 is journaled in the usual manner in the frame and is provided with the usual pulley 3. The shaft 2, the cutter

head 4 and the pulley 3 may be of any desired construction, inasmuch as the cutting mechanism does not pertain to the present invention, except that such parts must necessarily be present.

The shaft 5 is journaled in the frame 1 and has mounted thereon the roller 6, which 50 roller imparts movement to the lower endless conveyer 7, said conveyer being constructed in the usual manner and is extended rearward a sufficient distance to provide sufficient surface to receive the material 55 designed to be cut. It will be understood that the rear end of the endless conveyer is to be located around a roller, but owing to the fact that the construction is common and well known and has no specific reference to 60 the present invention the same is not illustrated. Upon the shaft 5 is securely mounted the clutch member 8, which clutch member is designed to be coupled and uncoupled to and from the drive sprocket wheel 9 at one 65 side of which wheel is located the long pinion 10. The drive sprocket wheel 9 and the long pinion 10 are preferably formed integral with each other and also the clutch member 11, said clutch member 11 being for 70 the purpose of engagement with the fixed clutch member 8. The drive sprocket wheel 9 and the long pinion 10 are slidably and loosely mounted upon the shaft 5. For the purpose of continuously rotating the sprocket 75 wheel 9, the shaft 2 is provided with the sprocket wheel 12 from which sprocket wheel leads the sprocket chain 13.

The feed roller 14 is securely mounted upon the shaft 15, which shaft is journaled 80 in the frame and for the purpose of communicating rotary motion to the shaft 15 and the roll 14 the gear wheel 16 is provided, which gear wheel meshes with the pinion 10. When the machine is running normal 85 the shaft 5 runs in the direction to move the top member of the endless conveyer 7 toward the feed roller 14, and owing to the fact that the roller 6 is securely mounted upon said shaft the top portion of said 90 roller will also move toward the roller 14,

said roller 14 being the underfeed roller. The sprocket wheel 9 which is driven by the sprocket chain 13 leading from the sprocket wheel 12, which is fixed to the knife head 5 shaft 2 will cause said wheel 9 to rotate in the opposite direction from the shaft 5 upon which it is mounted.

Upon the shaft 15 is securely mounted the gear wheel 17 and the clutch member 18, 10 said gear wheel 17 and clutch member 18 being securely mounted upon the shaft 15. Upon the shaft 15 is also located the clutch member 19, which clutch member is preferably formed integral with the wheel 16, 15 said clutch being in engagement when the machine is in cutting action. Directly above the lower feed roller 14 is located the upper endless conveyer 20, which is located around the roller 21 said roller being securely mounted upon the shaft 22, said shaft 20 being journaled in the swinging links 23, said shaft passing through slots 24 to allow the upper endless conveyer 20 together with its propelling roller to move to and from the lower feed roller 14, so as to compensate for 25 different amounts of thickness of material fed into the machine proper. The feed mechanism being of ordinary construction has no specific reference to the present invention, except that it must be necessarily present in order to provide a perfect working device.

For the purpose of communicating rotary motion to the endless conveyer the two intermediate gear wheels 25 and 26 are provided, the gear wheel 26 meshing with the gear wheel 27 which is mounted upon the shaft 22 and for the purpose of holding all 30 of these various gear wheels in proper mesh regardless of the position of the endless conveyer 20 and its roller 21 the links 23 and 28 are provided. For the purpose of communicating rotary motion to the various gear wheels 25, 26 and 27, the gear wheel 17 35 is provided and is securely mounted upon the shaft 15.

In the operation of feed cutters it is frequently desirable and even necessary to reverse the feeding mechanism so that if in 40 the event any article or articles should be dropped or accidentally placed in position to be fed into the machine the feeding action can be reversed, thereby preventing the breaking or injuring of any of the parts 45 such as the knives upon the cutter head coming in contact with articles liable to break or injure the knives. In the operation of feed cutters careless operators are liable to drop tools such as wrenches upon the feed 50 apron or material and in order to reverse the feeding mechanism I provide means whereby the material or the articles liable to injure the machine may be carried backward or away from the cutting head without stop-

ping the running of the machine proper. 65 In order to accomplish this reverse movement I provide the clutch members 8 and 11 and the clutch members 18 and 19. The clutch members 8 and 11 being mounted upon the shaft 5 and the clutch members 70 18 and 19 upon the shaft 15. When it is desired to reverse the feed action, the clutch members 18 and 19 are disconnected and the clutch members 8 and 11 simultaneously 75 coupled or connected and when the clutch members 8 and 11 are connected the sprocket gear wheel 9 and the shaft 5 will rotate in the same direction or in a backward direction from the cutter head proper, but when the clutch members 18 and 19 are coupled 80 and the clutch members 8 and 11 uncoupled, the shafts 5 and 15 will rotate in the opposite direction from that of the sprocket wheel 9 or in the direction to move the material designed to be cut toward the cutting head 85 mounted upon the shaft 2.

For the purpose of providing means for reversing the feed action a lever 29 is provided, which lever is pivotally connected to suitable ears or flanges fixed to the frame 90 in any convenient and well known manner. The bottom or lower end of the lever 29 and below its pivotal point is provided with the yokes 31 and 32, which yokes are for the purpose of engaging the sliding block or 95 head 33 and the clutch member 19 and when the lever is moved in one direction the clutch members 8 and 11 will be coupled together and the clutch members 18 and 19 will be uncoupled. As the lever is moved 100 in this direction the sliding head 33 will come in contact with the end of the long pinion 10, sliding said pinion upon the shaft 5, until the clutch members 11 and 8 are properly connected together, said clutch 105 members being preferably of the frictional type. When the lever 29 is moved in the opposite direction the clutch members 11 and 8 will be disconnected and the members 18 and 19 coupled together. It will be understood 110 that only a slight movement of the lever 29 is necessary to couple and uncouple the clutches, the various clutch members 11, 8, 18 and 19 should be so adjusted that the action of the reverse lever 29 will not bring 115 both clutches in relationship or coupled connection at the same time, but in order to prevent any jarring or possible accident one of the clutches preferably the one located upon the shaft 5 is of the frictional type so that 120 there will be no positive coupling together of the frictional clutch until after the interlacing clutch members 18 and 19 have been entirely disconnected or uncoupled. It is not deemed necessary to enter into a detailed description of the action of the feed 125 cutter proper as it does not pertain to the merits of the present invention. The devices

for reversing the feed mechanism having to do with the present invention, and may be employed and used regardless of the specific construction of the cutter head and the feed mechanism proper.

When the feed cutter is in operation, that is feeding devices are moved in the direction to convey the material to the cutter head to be acted upon, the feed roller 14 is driven by the pinion 10 the gear wheels 16 meshing therewith and the coupled clutch members 18 and 19. The clutch member 18 is securely mounted upon the shaft 15 and upon which shaft 15 is securely mounted the sprocket wheel 34 from which sprocket wheel leads the drive chain 35 to the sprocket wheel 36, which sprocket wheel is securely mounted upon the shaft 5. While the clutch members 18 and 19 are connected together the sprocket wheel 34 is the driving one and the sprocket wheel 36 is the driven one and the drive chain and the upper member of the drive chain moves in the direction of the arrow A. This drive chain communicates rotary motion to the shaft 5 and in turn imparts movement to the endless conveyer 7. The upper member of the endless conveyer being moved in the same direction as the drive chain 35 indicated by the arrow A. When the clutch members 18 and 19 are disconnected and the clutch members 8 and 11 connected the direction of motion of the shaft 5 is reversed and the sprocket wheel 36 becomes the driving one and the sprocket wheel 34 the driven one; and when the clutch members 8 and 11 are connected and the clutch members 18 and 19 disconnected the upper member of the drive chain 35 moves in the direction of the arrow B.

Having fully described my invention what I claim as new and desire to secure by Letters Patent, is—

1. In gearing of the class described, the combination of a suitable frame, a shaft journaled in said frame, a fixed clutch member carried by said shaft, a pinion slidably mounted upon said shaft, said pinion being provided with a clutch face adapted to engage said fixed clutch member, a second shaft journaled in said frame, a fixed clutch member carried by said second shaft, a gear slidably mounted upon said second shaft and meshing with said pinion, said gear being provided with a clutch face adapted to engage said second fixed clutch member, means for sliding said gear and said pinion upon their respective shafts, means for rotatably connecting the shafts independently of the clutch members and means for continuously rotating said pinion.

2. In gearing of the class described, the combination of a suitable frame, a shaft journaled in said frame, a fixed clutch mem-

ber carried by said shaft, a pinion slidably mounted upon said shaft, said pinion being provided with a clutch face adapted to engage said fixed clutch member, a second shaft journaled in said frame, a fixed clutch member carried by said second shaft, a gear 65 slidably mounted upon said second shaft and meshing with said pinion, said gear being provided with a clutch face adapted to engage said second fixed clutch member, a sliding block located upon said first named 70 shaft, a pivoted lever provided with yokes, one of the yokes of the pivoted lever being adapted for engagement with the sliding block and the other yoke being adapted for engagement with the sliding gear, means for 80 rotatably connecting the two shafts together independently of the clutch members and means for continuously rotating said pinion.

3. In gearing of the class described, the combination of a suitable frame, a shaft 85 journaled in said frame, a fixed clutch member carried by said shaft, a loose clutch member slidably mounted upon said shaft, said loose clutch member provided with gear teeth, a second shaft journaled in said frame, 90 a fixed clutch member carried by said second shaft, a loose clutch member slidably mounted upon said second shaft, said last named loose clutch member being provided with gear teeth adapted to mesh with the 95 gear teeth upon the first named clutch member, means for rotatably connecting the shafts independently of the clutch members, means for simultaneously coupling the clutch members upon either of the shafts 100 and uncoupling the clutch members upon the other shaft and means for continuously rotating one of the loose clutch members.

4. In gearing of the class described, the combination of a frame, parallel shafts journaled within said frame, fixed clutch members carried by said shafts, loose clutch members slidably mounted upon said shafts, said loose clutch members being rotatably connected, means independent of said clutch 105 members for rotatably connecting said shafts, means for rotating one of said loose clutch members and means for coupling and uncoupling said clutch members.

5. In gearing of the class described, the 115 combination of a suitable frame, a driving shaft, a sprocket wheel carried by said driving shaft, parallel shafts journaled in said frame, a fixed clutch member carried by one of said parallel shafts, a sprocket wheel 120 slidably mounted upon said shaft and provided with a clutch face adapted to engage said fixed clutch member, a pinion formed integral with said slidably sprocket wheel, a fixed clutch member carried by the second of said parallel shafts, a gear wheel slidably mounted upon said second parallel shaft, and provided with a clutch face

adapted to engage said last named fixed clutch member, said gear wheel being adapted to mesh with said pinion, a sprocket chain connecting said first named sprocket wheel and said slideable sprocket wheel means for alternately sliding said slideable sprocket wheel and said slideable gear wheel into engagement with the adjacent fixed clutch member and means for rotatively connecting said parallel shafts together independently of said clutch members.

In testimony that I claim the above, I have hereunto subscribed my name in the presence of two witnesses.

CHARLES F. HALDEMAN.
